UNITED STATES PATENT OFFICE

WALTER H. UNVERSAW, OF KOKOMO, INDIANA

DESIGN FOR A PIN

Application filed March 17, 1932. Serial No. 43,219. Term of patent 3½ years.

To all whom it may concern:

Be it known that I, WALTER H. UNVERSAW, a citizen of the United States, residing at Kokomo, in the county of Howard and State of Indiana, have invented a new, original, and ornamental Design for a Pin, of which the following is a specification, reference being had to the accompanying drawing, forming part thereof.

I claim:—

The ornamental design for a pin as shown.

WALTER H. UNVERSAW.
